UNITED STATES PATENT OFFICE

152,958

DESIGN FOR A LINK CHAIN FOR A BRACELET OR SIMILAR ARTICLE

Joseph Goldblatt, New York, N. Y.

Application December 27, 1948, Serial No. 150,368

Term of patent 7 years

(Cl. D45—4)

To all whom it may concern:

Be it known that I, Joseph Goldblatt, a citizen of the United States and a resident of the city, county, and State of New York, whose post office address is 74 West 46th Street, New York 19, New York, have invented a new, original, and ornamental Design for a Link Chain for a Bracelet or Similar Article, of which the following is a specification, reference being had to the accompanying drawing, forming a part thereof, in which:

Figure 1 is a top plan view of a link chain for a bracelet, or similar article, showing my new design;

Figure 2 is a side elevational view thereof; and Figure 3 is an end view of a single link unit.

I claim:

The ornamental design for a link chain for a bracelet or similar article, as shown.

JOSEPH GOLDBLATT.
